UNITED STATES PATENT OFFICE.

ISAAC B. ALTER, OF ROSSVILLE, KANSAS.

CHECK-BOOK.

SPECIFICATION forming part of Letters Patent No. 517,323, dated March 27, 1894.

Application filed June 1, 1893. Serial No. 476,268. (No model.)

To all whom it may concern:

Be it known that I, ISAAC B. ALTER, of Ross-
ville, in the county of Shawnee and State of
Kansas, have invented a new and Improved
5 Check-Book, of which the following is a full,
clear, and exact description.

The object of the invention is to provide a
new and improved check book, which is sim-
ple and durable in construction, and arranged
10 to permit of conveniently removing the checks
and of replacing the check tab when used up,
without requiring an entirely new book.

The invention consists of a casing having
a pocket and a check tab adapted to be fas-
15 tened to the inside of the pocket.

The invention also consists of certain parts
and details and combinations of the same, as
will be fully described hereinafter and then
pointed out in the claims.

20 Reference is to be had to the accompanying
drawings forming a part of this specification,
in which similar letters of reference indicate
corresponding parts in all the figures.

Figure 1 is a perspective view of the im-
25 provement with the casing open, and parts of
the pocket removed. Fig. 2 is a sectional
plan view of the same on the line 2—2 of Fig.
1. Fig. 3 is a perspective view of the guide-
way for the tab; and Fig. 4 is a perspective
30 view of the tab carrier.

The improved check book is provided with
a suitably constructed case A, preferably
made of leather, with a pocket B adapted to
be closed at its mouth by a flap C. In the
35 pocket B, and at the inside thereof, is secured
a guide-way D, preferably made of sheet
metal, and adapted to be engaged by a slide
E', formed on the back of the carrier E, made
in the form of a plate and adapted to receive
40 the tab F carrying the checks. The carrier
E is preferably formed at its upper end with
points E², adapted to be bent over and hooked
into the top edge of the check tab F, as is
plainly illustrated in Fig. 1, the lower end of
45 the said carrier E being bent over to form a
hook E³, adapted to engage the back of the
check tab F, so that the hook E³ in con-
nection with the points E² securely holds the

tab in place on the carrier. The tab F is at-
tached to the carrier in the manner described, 50
and at the time the carrier is slid outside of
the pocket along the guide-way D, the casing
then being in an open position. When at-
tached to the carrier the latter with the tab
can be readily slid into the pocket to prevent 55
the check from being soiled when not in use.

For using the device the operator opens the
casing or book, then slides the carrier out
onto the open flap C, whereby the tab is fully
exposed to permit of filling out the top check 60
in the usual manner, and then tearing the
same off for further use. The carrier with
the tab is then moved back into the pocket.
It will also be seen that when all the checks of
the tab have been used up, then the carrier E 65
is moved out on the guide-way D, and the stiff
back of the tab is then detached from the car-
rier and a new tab is attached to the latter.

Having thus fully described my invention,
I claim as new and desire to secure by Letters 70
Patent—

1. A check book, comprising a casing hav-
ing a pocket, and a carrier constructed to re-
ceive and support a check tab, and connected
to the casing within the pocket to slide in and 75
out of the same, substantially as described.

2. A check book, comprising a casing hav-
ing a pocket and provided with a guide way
on the interior of the pocket, and a check tab
carrier engaging and sliding in the said guide 80
way, substantially as described.

3. A check book comprising a casing pro-
vided with a pocket having a fixed guide-
way, a carrier formed with a slide adapted to
engage the said guide-way, and a check tab 85
secured on the said carrier, substantially as
shown and described.

4. A check book provided with a check tab
carrier, formed of a plate having a slide and
points or hooks for engagement with the said 90
tab, substantially as shown and described.

ISAAC B. ALTER.
